UNITED STATES PATENT OFFICE.

WILLIAM WALKER AND JOHN B. LEMLEY, OF SOUTHBIDGE, MASSACHUSETTS.

TROLLEY-ACTUATED CIRCUIT-CLOSER.

1,366,304.

Specification of Letters Patent. Patented Jan. 18, 1921.

Application filed October 14, 1920. Serial No. 416,890.

To all whom it may concern:

Be it known that we, WILLIAM WALKER and JOHN B. LEMLEY, citizens of the United States, residing at Southbridge, in the county 5 of Worcester and State of Massachusetts, have invented certain new and useful Improvements in Trolley-Actuated Circuit-Closers, of which the following is a specification.

- 10 This invention relates to means for momentarily closing an electric circuit to cause a desired result, as to set a signal, for example. While it is adapted particularly to be associated with a trolley-wire in such 15 manner that it will be operated by a wheel moving along the wire to close a circuit of a signal system and set a signal, it also may be mounted to be operated by some other moving part.
- 20 It is an object of the invention to provide a device of that character so arranged that it will operate to close and to keep closed an electric circuit for the period required to effect the desired result and that automatically will open the circuit after accomplishment 25 of the result.

When read in connection with the description herein, the details of construction, arrangement of parts, and manner of use of 30 the invention will be apparent from the accompanying drawing, forming part hereof, wherein an adaptation of the invention is disclosed in association with an electric traction system.

35 While the disclosures herein exemplify what now is considered to be a preferable embodiment of the invention, it is to be understood that it is not the intention to be limited necessarily thereto in interpretation 40 of the claims, as modifications and adaptations within the limits of the claims can be made without departing from the nature of the invention.

Like reference-characters refer to corresponding parts in the views of the drawing, 45 of which—

Figure 1 is a side elevation of the circuit-closer, certain parts being broken away;

Fig. 2 is a plan view;

50 Fig. 3 is a view of the circuit-closer mounted in association with a trolley-wire; and

Fig. 4 is a view of the trip-arm.

Having more particular reference to the 55 drawing, 4 designates a base member, which

is intended to be mounted in a substantially horizontal position.

Near one end, the base member has a raised portion or enlargement 5, and a vertically-disposed slot or elongated opening 6 extends 60 through the enlargement and base member.

A pin 7 in the base member extends substantially in horizontal position across the slot, and on the pin and in the slot is rockably mounted a trip-arm 8. The lower portion of the arm depends below the base, and it is bifurcated to afford legs 9 arranged to straddle a trolley-wire. The upper end 10 of the arm is rounded and is disposed normally in contact with a flat spring member 11. The member 11 is secured at one end by fastenings 12 to the enlargement 5, it extends over the slot, and it has a rounded depressed terminal portion or shoulder 13 that is normally outside of the upper end 75 of the arm.

The base member 4 and an end of the enlargement 5 are formed with a seat 14, in which normally rests a rollable weight 15 of electrically conductive material, the weight 80 preferably being a ball or of spherical shape.

A track of two inclined separated members of electrically-conductive material arranged to be traversed by the weight extends 85 from a place near the seat 14 upwardly to a standard 16 on the opposite end portion of the base. The track preferably is formed of two copper rods 17, the lower ends 18 of which are turned outwardly and 90 secured to the base by fastenings 19, and the upper end portions 20 of which extend through the standard and are connected by conductors 21 with the circuit to be closed. The weight is kept from jumping from its 95 seat and from the track by guard-rods 22 carried by the enlargement 5 and the standard 16 over and in spaced relation with respect to the track.

The base and its enlargement and the 100 standard and the guard-rails should be of non-conductive material, or the track should be mounted in insulation, in order to avoid short circuits, and for the same reason the means of mounting the device should be 105 insulated.

Normally the trip-arm 8 is in substantially vertical position, with its upper end inside of the depressed shoulder 13 of the spring, and the weight 15 rests in the seat 110

14 against the end of the enlargement 5 adjacent to and out of contact with the trip-arm. The spring holds the arm normally out of contact with the weight. When the 5 trip-arm is struck in the direction indicated by the arrow in Figs. 1 and 3, as by a passing trolley-wheel, the arm rocks, its upper end is driven past the shoulder 13 of the spring, and it strikes the weight and drives 10 it upwardly on the track. After the weight loses its momentum thereby given to it, it returns by gravity on the track and off of it into its seat, where it is out of contact with the track. During the period the 15 weight is on the track members, it closes the electric circuit of which those members are a part, and a signal is set or other action performed for which the device is installed. On passage from contact with the 20 track, the circuit, of course, again is open, and the weight strikes the upper portion of the trip-arm and drives it back to its normal position inside of the shoulder 13. Recession of the weight then is stopped by the 25 end of the enlargement 5.

One method of associating the device of this invention with an overhead-trolley traction system is disclosed by Fig. 3, wherein 30 A designates the trolley-supporting poles and B a rigid cross support carried by the poles. From such a support depends a stud C having clench-ears D engaging and supporting the trolley-wire E, which is the electric supply conductor, and along which 35 travels the contact member on trolley-wheel F.

The device may be mounted by disposing the stud C through one end portion of the base member 4 and by disposing a similar 40 stud C' through the other end portion thereof. The device is placed so that the track for the weight 15 is inclined downwardly in the direction the trolley-wheel is moving when it is desired to operate the device. 45 Thus, when that wheel strikes the trip-arm, the weight will be driven in the opposite direction onto its track and the circuit thereby closed.

Of course, on a double-track road, where 50 the traffic on one track normally is in the same direction, the circuit-closers will be placed to be operated by movement of the trolley-wheels moving in that direction. On a single-track road, where traffic is in both 55 directions, the circuit-closers will be placed and disposed at various places in accordance with the direction of movement of the trolley-wheels it is desired to have the circuits closed. When the trip-arm of a circuit-closer set for operation by a trolley-wheel moving in one direction is struck by a wheel moving in the opposite direction, the upper portion of the arm, of course, will 60 be moved away from the weight and the circuit will not be closed.

Having thus described our invention, what we claim as new, and desire to secure by Letters Patent, is—

1. A circuit-closer comprising inclined electrically-conductive rails arranged to be 70 connected with an electric circuit, an electrically-conductive weight normally out of contact with and arranged to traverse said rails, and means for driving said weight onto said track, the arrangement being such 75 that said weight thereafter will return by gravity to normal position off said rails.

2. A circuit-closer comprising inclined electrically-conductive rails arranged to be 80 connected with an electric circuit, an electrically-conductive weight normally out of contact with and arranged to traverse said rails, and a rockable arm arranged to drive 85 said weight onto said track, the arrangement being such that said weight thereafter will return by gravity to normal position off said rails.

3. A circuit-closer comprising inclined electrically-conductive rails arranged to be 90 connected with an electric circuit, an electrically-conductive weight normally out of contact with and arranged to traverse said rails, a rockable arm arranged to drive said weight onto said track, and a spring normally holding said arm out of contact with 95 said weight, the arrangement being such that said weight will return by gravity to normal position off said rails, strike said arm, and return it to normal position.

4. A circuit-closer comprising inclined 100 electrically-conductive rails arranged to be connected with an electric circuit, an electrically-conductive weight normally out of contact with and arranged to traverse said rails, a guard member retaining said weight 105 in place, and means for driving said weight onto said rails, the arrangement being such that said weight thereafter will return by gravity to normal position off said rails.

5. A circuit-closer comprising a base having 110 a seat, electrically-conductive rails inclined upwardly from said seat, an electrically-conductive weight normally in said seat out of contact with and arranged to traverse said rails, and means for driving 115 said weight onto said rails, the arrangement being such that said weight will return by gravity from said rails into said seat.

6. A circuit-closer comprising a base having 120 a seat, electrically-conductive rails inclined upwardly from said seat, an electrically-conductive weight normally in said seat out of contact with and arranged to traverse said rails, and a rockable arm in said base arranged to be struck by a moving 125 object and to drive said weight onto said rails, the arrangement being such that said weight will return by gravity from said rails into said seat.

7. A circuit-closer comprising a base hav- 130

- ing a seat, electrically-conductive rails inclined upwardly from said seat, an electrically-conductive weight normally in said seat out of contact with and arranged to traverse said rails, a rockable arm on said base arranged to be struck by a moving object and to drive said weight onto said rails, and a spring normally holding said arm out of contact with said weight, the arrangement being such that said weight will return by gravity from said rails into said seat.
8. In a traction system including an electric-supply conductor and a contact member movable thereon, the combination, with a signal circuit, of a circuit-closer therefor comprising inclined electrically-conductive rails connected with said circuit, an electrically-conductive weight normally out of contact with and arranged to traverse said rails, and a rockable arm positioned to be struck by said contact member and to drive said weight onto said rails, the arrangement being such that said weight will return by gravity from said rails to normal position.
- 15
- 16
- 20

by gravity from said rails to normal position.

9. In a traction system including an electric-supply conductor, a stud supporting said conductor, and a contact member movable on said conductor, the combination, with a signal circuit, of a circuit-closer therefor comprising a base supported by said stud, inclined electrically-conductive rails on said base connected with said circuit, an electrically-conductive weight normally out of contact with and arranged to traverse said rails, and a rockable arm depending from said base adjacent to said conductor arranged to be struck by said contact member and to drive said weight onto said rails, the arrangement being such that said weight will return by gravity from said rails to normal position.
